UNITED STATES PATENT OFFICE.

EDWARD SMITH, OF TUSCOLA, ILLINOIS, ASSIGNOR OF ONE-HALF TO
EMERY O. SMITH, OF SAME PLACE.

COMBINED TACK-DRIVER AND CARPET-STRETCHER.

SPECIFICATION forming part of Letters Patent No. 651,729, dated June 12, 1900.

Application filed February 2, 1900. Serial No. 3,714. (No model.)

To all whom it may concern:

Be it known that I, EDWARD SMITH, a citizen of the United States, residing at Tuscola, in the county of Douglas and State of Illinois, 5 have invented a new and useful Combined Tack-Driver and Carpet-Stretcher, of which the following is a specification.

This invention relates to devices for driving tacks and stretching carpets when combined in a single instrument; and one object of the invention is to provide a cheap and simple structure in which the carpet may be stretched to the desired tension, and the tack may then be driven in its proper position to 15 hold the carpet.

A further object of the invention is to provide a structure in which a number of tacks may be placed in the carrier and may be successively fed into a funnel-shaped tack-guide 20 for engagement by a driving-plunger.

An object of the invention also is to so connect the stretcher and driver that one may be folded against the other without precluding the operation of the driver.

25 In the drawings forming a portion of this specification, and in which similar numerals of reference designate like and corresponding parts in the several views, Figure 1 is a perspective view of the implement in its unfolded position and with the plunger raised and ready for driving tacks. Fig. 2 is a front view showing the lower portion of the driver on an enlarged scale and illustrating the arrangement of the tacks in the carrying or feed 30 tube. Fig. 3 is a side elevation showing the lower end of the implement with the carpet-stretcher in its folded position.

Referring now to the drawings, the present invention comprises a post 5, having a handle 40 6 at its upper end, and upon which post is fixed a casing 7, which receives a slideable plunger in the form of a rod 8, having a knob 9 at its upper end, this plunger being adapted for reciprocation and to project below the casing 45 when moved to its normal position. Upon the lower end of the post 5 is fixed a plate 10, having a funnel-shaped guide 11 mounted thereon or formed integral therewith, this guide being formed to project above and below the plate and having the rear walls of

these projected portions cut away, as illustrated in Fig. 4. The downwardly-projecting portion 12 of the guide-funnel is tapered to form a tooth 13 for a purpose which will be presently explained. The slot in the rear 55 walls of the extensions of the guide-funnel are mutually alined and are continued through the plate 10, and in this slot of the plate is disposed a spring-finger 14, the lower end of which bears upon the inner face of the extension 12 to hold a tack yieldably thereagainst.

Against the rear edges of the upper extension 15 of the guide-funnel and between said funnel and the post 5 is disposed a plate 16, which is held against the post in any suitable 60 manner and in the upper edge of which is an arc-shaped recess 17 of somewhat more than one hundred and eighty degrees, and at one side of this recess there is a longitudinal extension 18, having a tapered notch 19 in its 65 edge adjacent the recess 17. A spring-finger 20 is fixed to the end of the plate 16 on the opposite side of the recess 17 from the projection 18, and this finger extends across the recess and has its free end bent upwardly to 70 lie against the upper face of the notch or slot 19 adjacent the outer end of the latter. The rear wall of the plate 16 is recessed, this recess extending from the upper end of the plate to substantially one-half the depth of 75 the recess 17, and in this recess in the rear of the plate is disposed the lower end of a slotted feed-tube 21, the upper end of which is pivoted to the post 5, as shown at Fig. 1, while its lower end, which lies in the said 80 slot in the plate 16, is adapted for swinging movement in said slot, whereby the slot of the tube may alternately register with the opening of the slot 17 and lie behind the projection 18, this feed-tube being adapted to be 85 held yieldably in operative relation to the slot 17 by means of a spring-finger 22, carried by the extension or projection 18. It will thus be seen that if a tack be placed in the feed-tube 21 with its point to project through 90 the slot thereof and if the tube be held to lie behind the projection 18 the tack will fall upon the upper end of the projection until the feed-tube is rocked to its operative position, when the tack will drop to the spring 95 100

20. The return movement of the feed-tube will then move the tack into the notch 19 and below the spring 20, and the return movement of the tube will precipitate the tack 5 into the recess 17. When the tack falls into the recess 17, its head will strike upon the base of the recess, causing the tack to tilt and fall point downward into the guide-funnel and in engagement with the spring 14.

10 If the plunger 8 be then moved downwardly, it will engage the tack and force it through the guide-funnel and into a board of the floor.

In order to automatically rock or oscillate the feed-tube under the influence of the plunger, a rock-lever 23 is mounted upon the face of the post 5 and with its lower end against the side of the guide-tube at the opposite side from the spring-finger 22. The upper end of the lever 23 has a curved flange 24, which is 15 adapted for engagement by the plunger to rock the lever and move the feed-tube to lie behind the projection 18, as illustrated in Fig. 2. When the plunger is raised, it passes from engagement with the flange 24 and permits 20 the lever 23 to move under the influence of the spring-finger 22, which moves the feed-tube 21 into registry with the recess 17. Thus, as illustrated in Fig. 2 of the drawings, a number of tacks may be placed in the slotted feed-tube and the plunger may be reciprocated to feed them successively to the guide-funnel, from which they will be driven by engagement of the plunger.

The carpet-stretching portion of the present invention includes a lever 25, adapted 35 for operation either by the hand or foot, and which lever is connected with the post 5 above its lower end through the medium of links 26, whereby the lever may be moved with a swinging motion to project its end beneath the post. This end of the lever has a bifurcated plate 27, secured thereto in a position to receive the extension 12 of the guide-funnel between the bifurcations thereof, and upon the 40 under side of this bifurcated plate are teeth 28. The movement of the lever 25 in one direction upon its pivotal connection with the links 26 is limited by a metallic strap 29, which is passed transversely of the under 45 side of the lever and has its ends bent upwardly between the links 26 and then bent outwardly and downwardly to lie against the outer faces of the links, thus forming guides for the links.

50 With the structure described it will be seen that the tooth 13 may be engaged with the floor and that teeth 28 may be engaged with a carpet, after which the device may be manipulated to stretch the carpet in the direction of the teeth 13, so as to lie against the tooth, and that the plunger 8 may then be operated to drive a tack through the carpet and into the floor.

It will of course be understood that in practice 55 various modifications of the invention may be made, and as illustrated in Fig. 1 of the drawings there may be employed a guide

comprising a plate 30, having an upturned edge for guiding the tacks in their application to the feed-tube.

Any suitable materials may be employed for the various parts of the structure and any desired proportions may be used without departing from the spirit of the invention.

It will be noted that the spring 14 lies in 75 the hollow of the guide-funnel and that the lower end of the funnel has ears 12^a, which project rearwardly, so that this inclosure of the spring is maintained at all times. The object of this construction is to insure proper 80 co-operation between the spring and the funnel, so that the head of the tack will be securely held by the spring and funnel until the tack has been well started in the board. The proportions are such that the ordinary 85 carpet-tack is driven about one-third of its length into the board before the head of the tack passes from the inclosure of the ears 12^a.

What is claimed is—

1. A device of the class described comprising a post, a guide-funnel mounted upon the post and having a tack-retaining finger, a plate in the rear of the funnel and having a recess opening thereto, a projection adjacent the open end of the recess, and having a notch, a spring-finger disposed transversely of the recess and entering the notch in the projection, a slotted feed-tube pivoted upon the post and adapted for movement to align its slot alternately with the opening of said recess and with the notch, and a plunger mounted upon the post and adapted to enter the guide-funnel to drive a tack therefrom, said plunger being adapted for oscillation of the feed-tube.

2. A device of the class described comprising a post having a guide-funnel adapted to receive and hold tacks, said funnel having a slot in the rear and communicating therewith, a plate in the rear of the funnel and having a recess in its upper edge, a feed-tube disposed to discharge tacks into said recess to strike with the heads thereof against the bottom of the recess, a plunger adapted to enter the funnel and drive the tacks therefrom, and means operated by the plunger for oscillation of the feed-tube.

3. A device of the class described comprising a post having a guide-funnel and adapted to receive and hold a tack, a plate adjacent the funnel and having a recess communicating with the funnel, a projection upon the plate adjacent the recess, a notch in the projection, a spring-finger disposed transversely of the recess and having its free end curved upwardly and lying against the upper wall of the notch and inwardly thereof, a slotted feed-tube pivoted upon the post and having its lower end disposed behind the plate to register its slot alternately with the recess and the notch, means for holding the tube yieldably with its slot in registration with the recess, means for moving the tube to its opposite position, and a plunger adapted to operate said

moving means and to enter the guide-funnel to drive the tack therefrom.

4. A device of the class described comprising a post having a guide-funnel fixed thereto and provided with a tooth extending below the post, means for feeding tacks to the funnel, a plunger adapted to enter the funnel and drive the tacks therefrom, a lever having a bifurcated plate adapted to receive the tooth of the funnel and having teeth upon its under face, links pivoted to the lever and to

the post, and a strap engaged with the lever and having its ends bent over the links to form guides therefor.

In testimony that I claim the foregoing as 15 my own I have hereto affixed my signature in the presence of two witnesses.

EDWARD SMITH.
